UNITED STATES PATENT OFFICE.

ARTHUR HENRY HILL, OF BIRMINGHAM, ENGLAND.

SMALL-ARM.

1,165,256.

Specification of Letters Patent. Patented Dec. 21, 1915.

Application filed June 15, 1915. Serial No. 34,241.

To all whom it may concern:

Be it known that I, ARTHUR HENRY HILL, a subject of the King of Great Britain, residing at No. 16 Loveday street, Birmingham, England, have invented certain new and useful Improvements in Small-Arms, of which the following is a specification.

My invention consists of the improvements hereinafter described in breech loading small arms, the said improvements having for their principal objects to obtain a more efficient fastening of the barrel or barrels when closed to the body of the small arm.

According to my invention I provide a block capable of a sliding motion in a recess in the front face of the body of the small arm, the said block carrying in a hole or holes the loose striker or strikers of the action. The sliding motion of the said block may be effected by the turning of the ordinary top lever or other convenient means may be employed for effecting the requisite motions of the sliding block. The rear end of the barrel or barrels has one or more hook shaped parts or projections which on the closing of the barrel or barrels take into recesses between the sliding block and the sides of the recess in the front face of the body hereinbefore referred to, the sliding block having corresponding hook shaped parts or projections capable of engaging with the said hook shaped parts or projections on the rear end of the barrel or barrels when the latter are closed.

On the closing of the barrel or barrels the top lever or other operating means is turned so as to effect the sliding of the block carrying the loose striker or strikers and effect the engagement of the hook shaped parts or projections of the block with those on the barrel or barrels whereby a very efficient fastening of the gun results.

Where the motion of the sliding block is effected by the turning of the top lever the turning movement of the lever may be transmitted to the block through a slide with a notch in which an arm on the lower end of the top lever spindle engages, the said slide effecting the turning of a bell crank lever the end of one of the arms of which takes into a recess in the rear face of the sliding block.

I will further describe my invention in its application to a double barrel drop down small arm of the type commonly known as

an "under and over" gun in connection with which it is especially useful.

Figure 1 of the accompanying drawings represents partly in side elevation and partly in section so much of an "under and over" gun containing the improvements constituting my invention as is necessary to the understanding thereof, the gun being represented closed in full lines and indicated in its open position in dotted lines. Fig. 2 is a section on the line 2—2 Fig. 1 with the sliding block in its lowered or unfastening position. Fig. 3 is a side elevation partly in section. Fig. 4 is an inverted plan view of the underside of a part of the gun with the fixing plate of the trigger guard removed. Fig. 5 is a cross section taken on the dotted line 5—5 Fig. 3 looking in the direction of the arrow in Fig. 3, the lock carrying plates being omitted. Figs. 6 to 13, both inclusive, are detail views hereinafter particularly described. Figs. 14, 15 and 16 illustrate a modification of my invention hereinafter described.

The same letters of reference indicate the same parts in the several figures of the drawings.

a is the body of the gun having in its front face the somewhat large recess *a*¹ (best seen in Figs. 6 and 7 which are respectively a front elevation and plan of a portion of the body *a*), the said recess *a*¹ accommodating the block *b* shown detached in Figs. 8, 9 and 10, Fig. 8 being a front elevation of the block, Fig. 9 a side or edge view of the same and Fig. 10 a sectional plan, the section being taken in a plane indicated by the dotted lines 10—10 in Figs. 8 and 9.

The slide block *b* carries the loose strikers *c*, *c* which are inclined both to the vertical and horizontal, that is to say, the striker for the over barrel is downwardly and outwardly inclined and the striker for the under barrel is upwardly and outwardly inclined as is usual, as will be best understood by reference to Figs. 9 and 10. The said block *b* is retained in the recess *a*¹ of the body *a* by flanges *b*², *b*² on the rear side edges of the block engaging grooves *a*², *a*² at the inner end of the recess *a*¹, see Fig. 7.

The rear end of each of the barrels *d* is provided with an undercut arch-like extension *d*¹ and with hook shaped parts or projections *d*², *d*³ with which the parts *b*³, *b*⁴, *b*⁵ respectively of the block *b* are made to engage by the sliding of the said block upward

from the position represented in Fig. 2 to the position represented in Figs. 1 and 3 for fastening the barrels *d* in the closed position.

5 The motion of the block *b* is effected by the turning of the ordinary top lever *e* which is secured to the inclined spindle *f* indicated in dotted lines in Figs. 3 and 5, which spindle has on its lower end a cam or projection 10 *f*² (see Fig. 4). The said cam engages with projections *g*² on the sliding bolt *g* shown separately in plan of underside in Fig. 11, which, when in the fastening position engages with notches in the lumps *h*, *i* on the 15 underside of the under barrel. Into hole *g*¹ in the rear end of the sliding bolt *g* the nearly vertical arm *k*¹ of a bell crank lever *k*¹, *k*², *k*³ (shown detached in Figs. 12 and 13) depends, the free ends of the horizontal 20 arms *k*², *k*³ projecting into and engaging with notches or recesses in the rear face of the sliding block *b* as is best seen in Fig. 3.

I wish it to be understood that I do not limit myself to any particular means for 25 giving the sliding block the slight up and down motion to effect the fastening or unfastening of the barrels and in the arrangement Figs. 14, 15 and 16 I have represented a pin *l* (projection or the like) engaging with 30 an inclined channel or groove *m* in the rear face of the block *b*, the pin *l* projecting through a slot *n* in the body as is best seen in Fig. 15 in which the sliding block is omitted. The said pin *l* is in one with a 35 ring or collar which fits a square on the under side of the bush of the top lever *e*.

Although I have represented the parts constructed so as to effect the locking of the barrels by an upward sliding motion of the 40 block in the recess in the face of the body I

wish it to be understood that the parts may be constructed to effect the locking of the barrels by a downward or sidewise motion of the said block.

Having described my invention what I 45 claim as new and desire to secure by Letters Patent is:—

1. Small arms of the break down variety having in the front face of the body a recess for the reception of a block capable of a 50 limited vertical motion therein, the said block carrying loose strikers and having hook-shaped projections for engaging with corresponding parts on the rear end of the barrel or barrels, and means for effecting 55 the requisite motions of the block.

2. In small arms of the break down variety, mechanism for effecting the secure locking or fastening of the barrel or barrels when in the closed position comprising 60 a sliding block occupying a recess in the face of the body and having vertical movement, the said block carrying the loose striker or 65 strikers and having hook-shaped lips or projections which can be made to engage with corresponding parts on the rear end of the barrel or barrels, and the combination therewith of a bell crank lever one arm or pair of arms of which engage with the block and the other arm of which engages with a horizontal 70 sliding bolt which is actuated by a cam on the lower end of the top lever spindle.

In testimony whereof I have hereunto set my hand in presence of two subscribing witnesses. 75

ARTHUR HENRY HILL.
